[57] CLAIM

The ornamental design for a surgeon's scrub sink, as shown and described.

DESCRIPTION

FIG. 1 is a front elevational view of a surgeon's scrub sink showing our new design;

FIG. 2 is a left side elevational view thereof, the right side being a mirror image of the left side shown;

FIG. 3 is a top plan view thereof and

FIG. 4 is a perspective view taken from the top, front and left side thereof.

FIG. 1

FIG. 2

FIG. 3

FIG. 4
